UNITED STATES PATENT OFFICE.

STASH WIGIERT, OF BREMOND, TEXAS.

TOILET ARTICLE.

1,242,293.

Specification of Letters Patent. Patented Oct. 9, 1917.

Application filed May 23, 1917. Serial No. 170,391.

To all whom it may concern:

Be it known that I, STASH WIGIERT, a citizen of the United States, residing at Bremond, in the county of Robertson and State of Texas, have invented certain new and useful Improvements in Toilet Articles, of which the following is a specification.

This invention relates to toilet articles and has special reference to a combined comb 10 and brush.

More particularly the invention relates to a novel means of constructing a plurality of articles of this description and a cover therefor in such a way that the cover may 15 be used either alone or in connection with one of the articles as a handle for one or the other of said articles.

One important object of the invention is to improve the general construction of devices of this character.

A second important object of the invention is to provide a device of this character consisting of a comb and brush and cover, the different parts being so connected that 25 spring clutches will hold them in the desired positions.

With the above and other objects in view, as will be hereinafter apparent the invention consists in general of certain novel details 30 of construction and combinations of parts hereinafter fully described, illustrated in the accompanying drawing, and specifically claimed.

In the accompanying drawings, like characters of reference indicate like parts in the several views, and:—

Figure 1 is a side elevation of a combined comb and brush in folded position.

Fig. 2 is a back view thereof.

Fig. 3 is a section on the line 3—3 of Fig. 2.

Fig. 4 is a detail section on the line 4—4 of Fig. 2.

Fig. 5 is a view similar to Fig. 2 but 45 showing the cover turned back to form a handle for the brush.

Fig. 6 is a side view, partly in section, of the parts when arranged as in Fig. 5.

Fig. 7 is a view similar to Fig. 1 but 50 showing the comb in position for use, the cover and brush forming the handle for the comb.

Fig. 8 is a detail section showing the latch for holding the cover on the brush.

55 In carrying out the objects of this inven-

tion there is provided a brush having a back 10 and in the back face of this brush is a recess 11 while on the front face thereof there is provided the usual brush bristles 12. Projecting from one end of the brush 60 is a pair of spring arms 13 which are spaced at their free ends and provided with inwardly facing clutch elements 14.

In order to protect the bristles in traveling and also to form a handle for the brush 65 there is provided a hollow cover 15 from one end of which projects spring arms 16 spaced at their extremities and provided with outwardly facing clutch members 17 and inwardly facing clutch members 18, the 70 clutch members 17 fitting between and co-operating with the clutch members 14 and being so arranged that when the device is flattened as in Fig. 1 the spring clutch will tend to hold it in this flattened position and, 75 when the device is open as in Fig. 5, the spring clutch will tend to hold it in the open position. Moreover, in order to assist in holding the device closed there is provided on the free end of the cover 15 a spring 80 latch 19 engaging a bead 20 in a recess 21 in the brush back when the cover is folded, this construction being best seen in Fig. 8. Normally lying in the recess 11 is a comb 22 and from one end of this comb projects 85 an arm 23 having at its end outwardly facing clutch members 24 which lie between the clutch members 18 and are so engaged therewith that the comb may be either locked in position as shown in Figs. 2 and 5 or 90 may be locked in the position shown in Fig. 7. In the latter position it is to be observed that the brush back and cover 15 combine to form a handle for the comb 22. It will also be noted that the recess 11 is sufficiently 95 deep to completely house the comb when the entire device is folded as in Fig. 2.

The use of the device will be readily understood from the drawings, the parts being folded into position as shown in Fig. 1 for 100 packing; as in Fig. 5 for use as a brush, and as in Fig. 7 for use as a comb.

There has thus been provided a simple and efficient device of the kind described and for the purpose specified.

It is obvious that many minor changes may be made in the form and construction of the invention without departing from the material principles thereof. It is not therefore desired to confine the invention to the 110

exact form herein shown and described but it is wished to include all such as properly come within the scope claimed.

Having thus described the invention, what is claimed as new, is:—

The combination with a brush back having bristles projecting from one face thereof and a recess in the opposite face; of a pair of spring arms fixed at one end of said back and projecting therefrom in spaced relation, inwardly facing clutch elements on said arms, a bristle cover, a similar pair of spring arms fixed at one end of the cover and projecting therefrom in spaced relation, inwardly and outwardly facing clutch ele-

ments on the ends of said last arms arranged between and coöperating with the clutch elements on the first arms, a comb adapted to lie in said recess and having an arm extending from one end, and outwardly facing clutch elements at the end of the last-mentioned arm and lying between and coöperating with the clutch elements on the cover arms. 20

In testimony whereof I affix my signature. 25

STASH WIGIERT.
